UNITED STATES PATENT OFFICE.

ROBERT W. PAIN, OF NEW YORK, N. Y., ASSIGNOR, BY MESNE ASSIGNMENTS,
TO THE NATIONAL AUTOMATIC PIANO AND ORGAN MANUFACTURING
COMPANY, OF NEW YORK.

DEVICE FOR CONVERTING MOTION.

SPECIFICATION forming part of Letters Patent No. 268,528, dated December 5, 1882.

Application filed April 15, 1882. (No model.)

To all whom it may concern:

Be it known that I, ROBERT W. PAIN, a citizen of the United States, and a resident of New York, in the county and State of New 5 York, have invented a new and useful Improvement in Devices for Converting Reciprocating into Rotary Motion, of which the following is a specification.

This invention relates to that class of clutch 10 devices that are usually operated by pedals, and are adapted to drive sewing-machines, mechanical musical instruments, and other light machines.

The invention consists of two smooth-faced 15 wheels rigidly fixed on a shaft, and the combination, with each wheel, of an arm swinging on said shaft, of a pawl pivoted to the outer end of said arm and operating upward against said wheel, and of a fork adapted to rock up and 20 down on said shaft, and to transmit the movements of a pedal to the clutch device. Two of these combinations of wheel, arm, pawl, and fork are fixed on the shaft at such relative 25 angles that the regular reciprocating motions of the pedals to which they are respectively connected will cause said shaft to continuously revolve in one direction. The manner of the application of said pawls to the wheels being, however, unlike that common to other devices 30 of this character, inasmuch as each pawl becomes engaged against its respective wheel by the upward instead of the downward movement of the corresponding pedal.

Figure 1 is a vertical sectional elevation on 35 line $\alpha\alpha$, Fig. 2, showing my improved device applied to a machine. Fig. 2 is a front elevation showing the same. Fig. 3 is an enlarged plan of one of the elements of the clutch device. Fig. 4 is an enlarged partly sectional 40 side elevation of the same.

Similar letters of reference indicate corresponding parts.

In the drawings, A represents the case or frame of a mechanical musical instrument.

45 B is the horizontal driving-shaft, journaled in the sides of the case A.

C represent the clutch elements, each of which consists of a wheel, a, rigidly fixed on the driving-shaft B, of a fork, b, loosely fixed

on said shaft B, and inclosing between its fingers the wheel a of an arm, c, loosely fixed on said shaft B at a side of the wheel a, and extending forward with its free end resting on the cross-bar d of the fork b, and of a pawl, f, pivoted to the free end of the arm c on a side thereof, having its higher end in contact with the face of the wheel a, while its lower end rests on the cross-bar d. On the under side of the cross-bar d are two downward-projecting lugs, g, between which the upper end of a connecting-rod, l, is held by a rod, h, the lower end of said connecting-rod being jointed to a pedal, D, that is rigidly secured on a shaft, E. The outer ends of the pawls f being below the axes of the wheels a, and resting on the cross-bars d, while their inner ends are in contact with the peripheries of said wheels, it follows that an upward motion of a pedal, D, will force upward the outer end of its connected fork b, with the effect of forcing the nose or inner end 55 of the connected pawl f in contact with the wheel-periphery, which periphery is preferably covered with a band, m, of rubber, to prevent slipping; and by the continued upward movement of the pedal the said wheel is carried 60 around in correspondence with the ascending movement of the said fork b and pawl f, while a falling motion of the pedal will relieve the bite of the pawl upon the wheel by removing 65 the upward pressure of the cross-bar d from 70 the outer end of said pawl, and the fork b, arm 75 c, and pawl f will then fall with their respective pedal, leaving their wheel a and the shaft B free to be revolved by the upward movement of the other pedal and its connected 80 clutch elements. It will be seen, then, that when the operator forces one pedal down the other pedal is thereby forced upward, and that the clutch element of the falling pedal becomes 85 inoperative, while that of the rising pedal becomes operative. Hence a constant reciprocating 90 movement of said pedals will cause the driving-shaft B to continuously revolve in one direction.

I represents a roller provided with a pulley 95 or sleeve, H, that may be revolved in the same direction as the shaft B by a straight belt-connection, G, with a pulley, F, on the said

driving-shaft B; and herein the use of this clutch device offers an obvious advantage over those of the usual construction, which necessitates the use of a cross-belt to make the driven shaft rotate in the same direction as the driving-shaft.

I am aware that there are various clutch devices for converting reciprocating into rotary motion; but I am not aware that any of them operate or are constructed in the manner herein set forth.

I do not broadly claim two pawls operating alternately and by a single pedal, nor two pawls operating alternately upon opposite sides of the same wheel; nor do I claim broadly a single pawl operating upon the periphery of a wheel, nor two V-pointed pawls operating upon opposite faces of a V-grooved wheel, nor two pawls operating alternately on separate wheels and by two pedals; but,

Having thus described my invention, I claim as new and desire to secure by Letters Patent—

1. An improved device for converting reciprocating into rotary motion, composed of two like clutch elements, C C, each attached by a connecting-rod to a pedal that is rigidly fixed on a shaft, and consisting of a wheel, a, rigidly fixed on a driving-shaft, a fork, b, and arm

c, loosely fixed on said shaft, the former provided with cross-bar d, and a pawl, f, pivoted on the free end of said arm c, said elements being made operative by the ascending motions of their respective pedals, as set forth. 30

2. In a device for converting reciprocating into rotary motion, and operated by the ascending movements of the connected pedals, the combination, with the fixed wheels a a, of the swinging arms c c, and attached pawls f f, said wheels being made to revolve by the ascending movements of said pawls, as set forth. 35 40

3. As a means for converting reciprocating into rotary motion, the combination, with a pair of wheels rigidly fixed on a shaft, of two pawls acting alternately and made to operate on the wheel-faces by means of the ascending motion of connected pedals, substantially as herein shown and described. 45

In testimony that I claim the foregoing as my invention I have signed my name, in presence of two witnesses, this 14th day of April, 1882.

ROBERT W. PAIN.
